UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 18, 1921, Serial No. 452,820. Renewed January 27, 1926.

The present invention relates in general to automatic telephone systems, but is concerned more particularly with such systems as comprise a plurality of small automatic exchanges for use in rural communities, such exchanges being commonly known as community automatic exchanges; and the object of the invention generally speaking is to provide a variety of improvements in a system of this kind which tend to make the same more efficient and practical.

A special feature of the invention relates to improved circuit arrangements for an automatic connector switch whereby the operation of the connector under control of a calling line is prevented in case the line is grounded to such an extent as to interfere with the ringing and releasing operations which, in the ordinary course, will take place after the required connection is established.

A further feature is concerned with means in a connector switch for discriminating between calls received over local lines, and calls received over incoming trunk lines. When a call is received over a local line the connector does not reverse battery in the calling line, but whenever a call is received over an incoming trunk line the direction of current flow in the trunk line is reversed.

There are a number of other features, not now specifically mentioned, which relate to various circuit refinements, and which together with the ones pointed out above will be fully described hereinafter, with reference to the accompanying drawings in which there is shown sufficient of the apparatus in a system embodying the invention to enable the same to be described and understood.

Although the invention is applicable to systems differing in size and extent and employing any number of different exchanges, it has been found convenient for purposes of illustration to show a system comprising three small exchanges which are so located with respect to each other that the second exchange takes on the character of an intermediate exchange, and calls from the first exchange to the third exchange, and likewise from the third exchange to the first exchange are trunked through the second exchange. The first, or No. 1 exchange, is a manual exchange, while the No. 2 and No. 3 exchanges are community automatic exchanges. According to the usual practice the abbrevia-

tion C. A. X. is used to designate an exchange of the latter type, and this abbreviation will be used hereinafter.

Referring now to the drawings, the equipment shown in Fig. 1 is located in the No. 1 or manual exchange, and comprises the manual substation A with associated line equipment at the exchange, an operator's cord circuit O, and an outgoing trunk line comprising conductors 24 and 25 extending to the No. 2 exchange. There may be a group of trunk lines similar to the one shown, each of which is provided with trunk equipment such as is illustrated at the right of Fig. 1. The calling device S is common to all of these trunk lines and may be connected with any one of them for the purpose of controlling the automatic switches in the distant C. A. X.

At the No. 2 exchange the trunk line comprising conductors 24 and 25 terminates in the incoming connector switch H, shown in Fig. 2, each of the other trunk lines in the group being terminated in a similar switch. These incoming connector switches have access to the local lines in the No. 2 exchange and also to trunk lines which extend to the No. 3 exchange, or the second C. A. X.

Fig. 3 shows a local connector switch H', which is one of a group of similar switches used by the subscribers in the No. 2 exchange in completing local connections. The local connectors also have access to trunk lines extending to the No. 3 exchange, and to the group of trunk lines connecting with the No. 1 exchange, which includes the trunk line comprising conductors 24 and 25.

In Fig. 4 there are shown two of the local lines which terminate in the No. 2 exchange, together with their associated individual line switches C and C'. The line serving the substations A' to A³, inclusive, is a party line, while the line of substation A⁴ is an individual line. Fig. 4 also shows a repeater, which is indicated by the reference character D and which is associated with one of the trunk lines connecting with the No. 3 exchange. This trunk line comprises conductors 260 and 261 and extends through the repeater to normal conductors which are multiplied in the banks of the local and incoming connectors in the No. 2 exchange. A branch extends from the repeater to the individual line switch C², which, in common with the other line switches, has access to the local

connectors such as the connector H'. The line switch C² is used on calls incoming from the No. 3 exchange.

Fig. 5 is a detail showing how the private bank contacts are connected in the trunking levels of the connector switches.

Most of the apparatus used herein is of a well known type and consequently will not need to be described in detail. The telephone substations, including the manual substation A, Fig. 1, and the automatic substations A¹ to A⁴, inclusive, Fig. 4, are of the usual type in common use. The automatic substations, however, are each provided with calling devices such as the calling device S' and S² for controlling the automatic switches.

The individual line switches C, C' and C² are of the well known rotary type in which the wipers have no normal position and which move in a forward direction only. As commonly constructed, these line switches have semi-circular banks containing twenty-five sets of contacts, and two sets of wipers set at an angle of 180 degrees apart.

The local and incoming connectors, such as the connectors H' and H are of the usual Strowger vertical and rotary type, in which the bank contacts are arranged in horizontal rows, or levels, and are operated according to the well known two wire system of control. The switch circuits are shown complete and as they contain a number of novel features they will be described in detail hereinafter. The repeater D is used for repeating impulses over the associated trunk line when the same is used for calls to parties whose lines terminate in the No. 3 exchange, and is very similar to repeaters which have been commonly used before this. In view of the different switch control and signalling circuits used in the present system, however, it has been necessary to revise the circuits somewhat in order to accommodate the repeater to the modified functions which it has to perform. The operation of the circuits will be explained fully in the course of the detailed explanation.

The apparatus, having been described more or less in general, will now be described in connection with a detailed description of its operation. For this purpose it will be assumed that the subscriber at substation A desires to obtain a connection with the subscriber at substation A' whose number is assumed to be 89. When the subscriber at substation A removes his receiver, a circuit is closed for line relay 2. The line relay 2 upon energizing, lights the lamp L in front of the operator. The operator, upon noting the lighted condition of lamp L, inserts the plug of an idle cord circuit, such as cord circuit O, into the jack J. When this is done the cut off relay 3 energizes and removes the line relay 2 from

the circuit. This extinguishes the lamp L. The lamp L' is not lighted at this time because the relay 10 is energized over the subscriber's line loop and closes a shunt around the said lamp. The operator will now throw her listening key in order to converse with the calling subscriber and, upon learning that it is the subscriber at substation A' that the calling subscriber desires to be connected with, she inserts the other plug of the cord circuit in use into an idle jack associated with a trunk line to the nearer C. A. X., the jack J' for example, and therefore the supervisory lamp L² becomes lighted because there is no circuit closed at this time for relay 11. When the plug is inserted in jack J' as just described a circuit is closed across trunk conductors 24 and 25 as follows: from trunk conductor 24 by way of the normally closed contacts controlled by spring 22 of key K', normally closed contact controlled by spring 20, spring 16 and its working contact, winding of the polarized relay 17, and the normally closed contacts controlled by spring 21, to conductor 25. The effect of closing this bridge across conductors 24 and 25 will now be considered. When the bridge is closed as before described line relays 28 and 29 of connector H at the main exchange energize in series by way of the following path: from ground through relay 29, normally closed contacts controlled by armature 41, resting contact of armature 39 and said armature, trunk conductor 25, and thence by way of previously traced bridge to conductor 24, armature 37 and its resting contact, normally closed contacts controlled by armature 40, normally closed contacts controlled by armature 52, and relay 28 to battery. Both relays 28 and 29, 101 energize over the above circuit. The polarized relay 17, however, in the manual exchange, does not operate at this time due to the fact that the current is flowing in the direction opposite to that in which it must flow in order to operate the relay. Relay 29 upon energizing, operates release relay 30 at armature 47 and its working contact. Release relay 30, upon energizing, opens a point in the circuit of release magnet 49, 115 and prepares the circuit of the vertical magnet 48.

With this condition existing, the operator throws her key K' in such a direction as to operate springs 20 and 21 thereby inserting the calling device S into the bridge across the trunk conductors 24 and 25 and removing the polarized relay 17 therefrom. The operator may now operate her calling device in accordance with the first digit 8 of the desired number and when she does so line relay 29 of the connector H is deenergized eight times momentarily. Before going farther a certain detail in connection with the operation of relay 28 at this time will be con- 130

sidered. It will be noted that when the bridge across conductors 24 and 25 is interrupted at the calling device S relay 28 as well as relay 29 has its circuit broken. Now, if it should happen that there is a very heavy ground upon the conductor 24, relay 28 will not deenergize but will remain up throughout the series of impulses. This, however, in known switches, does not affect the operation of the switch for the line relay 29 operates as usual. In the present case, however, the circuit of the vertical magnet is held open at armature 44 of relay 28 in case that relay does not deenergize. Thus it is seen that if the ground on conductor 24 is enough to prevent the deenergization of relay 28 it also prevents the mechanical operation of the connector.

Assuming that the conductor 24 is not grounded sufficiently to prevent relay 28 from operating when the circuit is first interrupted at the calling device S, relays 28 and 29 both deenergize as soon as the calling device opens the circuit. That being the case the circuit for the vertical magnet 48 is closed as follows: from ground by way of armature 47 and its resting contact, armature 51 and its working contact, vertical off normal springs 56 and 54, resting contact of armature 44 and said armature, slow acting relay 31, and vertical magnet 48 to battery. By the operation of the vertical magnet the switch shaft and wipers are raised step by step until the wipers stand opposite the eighth level of bank contacts. Relay 31 is energized in series with the vertical magnet and being slow acting retains its armatures attracted throughout the vertical movement. The operation of relay 31 serves to maintain the circuit of the vertical magnet intact at armature 53 and its working contact after the off normal springs have shifted, as they do upon the first vertical step. Upon energizing, the relay 31 also places the resistance R into the circuit at armature 52 and removes relay 28 therefrom. This operation increases the flow of current to relay 29 and also allows it to operate over a circuit that is not so inductive as it would be were the relay 28 left in series. The entire removal of the relay 28 from the circuit during impulsive prevents its operation during impulsive after it once falls back. At the end of the vertical movement the slow acting relay 31 deenergizes and reinserts relay 28 into the circuit and removes resistance R therefrom while at armature 53 it shifts the operating circuit from the vertical magnet to the rotary magnet 69.

The operator may now operate her calling device in accordance with the second digit 9 in the desired number and when she does so the line relay 29 is deenergized nine times and thereby operates the rotary magnet 69 over the following circuit: from

ground by way of armature 47 and its resting contact, armature 51 and its working contact, vertical off normal springs 56 and 55, armature 53 and its resting contact, slow acting series relay 32, normally closed contacts controlled by armature 61, resting contact of armature 72 and said armature, and rotary magnet 69 to battery. By the operation of the rotary magnet the wipers are stepped around until they come to rest on the ninth set of contacts in the level opposite which they are raised. In this case they come to rest on the contacts 80-83, inclusive, these being the contacts in which the line of substation A' terminates. The slow acting relay 32 is energized in series with the rotary magnet and retains its armatures attracted throughout the rotary movement. At armature 59, relay 32, upon energizing, connects the resistance R in multiple with relay 28 so as to provide a better impulsive circuit for line relay 29, while at armature 60 it completes a circuit from grounded release trunk conductor 89 for relay 34. Relay 34, upon energizing, prepares the test circuit at armature 65 and its working contact. At the end of the rotary movement the slow acting relay 32 deenergizes and, upon so doing, opens the circuit of resistance R at armature 59, opens the original energizing circuit of relay 34 at armature 60, closes the busy test circuit at the normally closed contacts controlled by armature 60, and at armature 60 and its resting contact prepares a circuit for the lower winding of switching relay 35.

The operation now depends upon whether the called line is busy or idle. If the called line is busy there is a ground potential upon the test contact 82 with which the test wiper 78 is in engagement. That being the case relay 34 does not deenergize when its circuit is shifted by the falling back of armature 60 of relay 32 but is maintained energized over the following circuit: from ground by way of busy test contact 82, test wiper 78, armature 73 and its resting contact, armature 65 and its working contact, normally closed contacts controlled by armature 62, relay 33, normally closed contacts controlled by armature 66 of rotary magnet 69, normally closed contacts controlled by armature 60, and relay 34 to battery. Relay 33 energizes over the above traced circuit and upon so doing shifts its own circuit, and consequently that of relay 34, at armature 62 so that instead of ground being supplied by way of test contact 82 it is supplied by way of release trunk conductor 89 and armature 62 and its working contact. This is done in order that the connector will not cut in on the busy line in case it should become idle later. A further result of the energization of relay 33 is that it connects at armature 63 a lead

from the busy signalling machine B, to the lower heavy talking conductor. This latter operation gives the calling operator an audible busy signal and she, upon hearing it, will release the connection.

In the present case, however, we may assume that the line of substation A' is idle when called; that being the case, the deenergization of slow relay 32 is followed by 10 the deenergization of relay 34. Relay 34 upon deenergizing, completes at armature 65 the following circuit: from ground by way of release trunk conductor 89, armature 60 of relay 32 and its resting contact, lower 15 winding of switching relay 35, resting contact of armature 65 and said armature, resting contact of armature 73 and said armature, test wiper 78, test contact 82, release trunk conductor 85, switching relay 203 of line switch C, Fig. 4, and stepping magnet 202 to battery. Switching relays 35 and 203 energize in series over this circuit, and the latter clears the called line of its normal 20 battery and ground connections in the line switch C. It may be stated here that due 25 to an interlocking device (not shown) between the armatures of switching relay 203 and line relay 201 the armatures of switching relay 203 are operated only about half 30 way at this time and consequently the wipers are not connected up. In the connector H, when the switching relay 35 energizes it establishes a locking circuit for itself at armature 72 in series with the rotary magnet 69, at the same time disconnecting the operating circuit from the rotary magnet so that in case the calling device is turned again the wipers are not stepped around any further, prepares the 35 circuit of the ringing relay 34 at armature 71, and at armatures 70 and 74 completes the connection to the line wipers 76 and 79.

The connection is now extended to the desired called line and in order to signal the 40 called subscriber, the operator throws the key K' to the opposite or ringing position, in which position the spring 22 is operated. Spring 22, upon operating, places direct ground upon conductor 24 and includes the 45 relatively high resistance R¹⁰ in the bridge across conductors 24 and 25. The function of resistance R¹⁰ will be explained fully hereinafter. In the connector H relay 28 remains energized and holds release relay 50 55 30 energized at armature 43, but relay 29, being no longer supplied with current due to the ground placed upon conductor 24 by spring 22 of key K', falls back and operates the ringing relay 34 by way of the following circuit: from ground by way of armature 47 of relay 29 and its resting contact, armature 51 and its working contact, armature 42 of relay 28 and its working contact, armature 71 and its working contact, and ringing relay 34 to battery. Ring-

ing relay 34, upon energizing, operates armatures 64 and 68 and thereby projects generator current out on the called line. This operation rings the bells at substations A² and A³ as well as the bell at the called substation A'. When the operator restores key K' to normal line relay 29 is again energized and at armature 47 breaks the circuit of ringing relay 34. This obviously results in the removal of ringing current from the 75 called line. Since there are more than one substation on the called line and all the bells are operated simultaneously, it is necessary that the ringing be done according to predetermined codes. This being the 80 case, the operator repeats the operation as many times as are necessary to send out the code of substation A' and if the subscriber thereat does not answer immediately the code is repeated as many times as may be 85 necessary to attract his attention.

When the subscriber at substation A' responds he removes his receiver from the hook and as soon thereafter as the ringing relay 34 is in normal position a circuit is closed 90 for the back bridge relay 27 by way of the normally closed contacts controlled by armatures 37 and 39 of relay 26. Relay 27, upon energizing, operates armatures 40 and 41. This operation places the upper talking condenser in the circuit and reverses the incoming trunk conductors as regards their connection with relays 28 and 29. This results in the operation of polarized relay 17 in the manual exchange, which, upon operating, 100 closes a circuit for supervisory relay 11 by way of impedance 18. Supervisory relay 11, upon operating, extinguishes supervisory lamp L². The operator, upon noting that lamp L² is extinguished, knows that the 105 called subscriber has answered.

The calling and called subscribers may now converse with each other in the usual manner and when the conversation is finished both subscribers replace their receivers. When the receiver is replaced at substation A the circuit of supervisory relay 10 is broken with the result that the supervisory lamp L' is lighted. The replacing of the receiver at substation A' opens the circuit of back bridge relay 27 of connector H which, upon falling back, reverses the trunk conductors 24 and 25 back to normal. When this is done polarized relay 17 retracts its armature and thus opens the circuit of supervisory relay 11. Supervisory relay 11, upon deenergizing, allows supervisory lamp L² to become lighted again. The operator upon noting the lighted condition of lamps L' and L² pulls down the connection.

When the plug is removed from jack J the cut off relay 3 deenergizes and restores the circuit conditions for the line of substation A to normal. When the plug is removed from jack J' the circuit for relays 28 and 29 125 130

of selector H is opened and the two relays accordingly deenergize. When relays 28 and 29 deenergize they open at armatures 43 and 47 the circuit of release relay 30. Release relay 30, upon deenergizing, completes the following circuit for release magnet 49: from ground by way of armature 47 and its resting contact, armature 51 and its resting contact, armature 38 and its resting contact, off normal springs 57 and 58, and release magnet 49 to battery. By the operation of the release magnet the switch shaft and wipers are restored to normal, the circuit of the release magnet being broken at off normal springs 57 and 58 when the switch shaft reaches normal position.

It might well be explained at this point the particular function for resistance R^{10} , Fig. 1, as well as for resistances R^7 and R^8 of substations A' and A⁴, and also resistance R^6 of repeater D. If we assume, in the case just described, that the operator has operated the key K' in such a direction as to operate spring 22 after the called subscriber has answered and reversed the direction of current flow in the conductors 24 and 25 it is easily seen that spring 22 would have, in that case, been connected by way of conductor 24 and the working contact of armature 40 and said armature, to relay 29. Accordingly this ground connection would not in that case be effective to hold the relay 28 energized and if at that time the bridge across the conductors 24 and 25 were entirely opened relay 28 would fall back with the result that the switch would be released. However, with the resistance R^{10} in the circuit, relay 28 is held energized and at armature 43 maintains release relay 30 energized. If, on the other hand, the resistance R^{10} were omitted and the gap thus produced were bridged by a conductor of comparatively low resistance the relay 29 of connector H would be slow to fall back, when the ringing key is operated due to the fact that it is practically short circuited by the ground placed on spring 22. This of course would result in a sluggish action of line relay 29 at this time which of course would be very undesirable. The other resistances mentioned in connection with resistance R^{10} are all placed where they are for the same reason.

It will now be assumed that the subscriber at substation A' desires to obtain connection with the subscriber at substation A⁴, whose number is 90. When the subscriber at substation A' removes his receiver a circuit is closed for the line relay 201 of the line switch C. Upon energizing, line relay 201 closes at armature 205 a circuit for switching relay 203 and stepping magnet 202 in series, and at armature 204 connects the test wiper 209 to the above circuit at a point between the switching relay and the stepping magnet. The operation now de-

pends upon whether the trunk line upon which the wipers of the line switch are standing is busy or idle. If the trunk line is busy there is a ground potential upon the test contact with which the test wiper 209 is in engagement; the switching relay 203 is short circuited and the stepping magnet 202, which interrupts its own circuit, is operated in the manner of a buzzer to advance the switch wipers step by step in search of an idle trunk line. In the present case, however, we may assume that when the call is initiated the trunk line upon which the wipers of the line switch are standing is idle. Under these circumstances when the line relay 201 is energized the switching relay 203 is not short circuited and the stepping magnet 202 is not operated because of the high resistance of said switching relay. The latter relay, however, is energized, grounds the test wiper 209 at armature 206, and at armatures 207 and 208 disconnects the line conductors 84 and 86, from the winding of line relay 201 and from ground respectively, and extends them by way of wipers 210 and 211, bank contacts 212 and 214, trunk conductors 101 and 103, armature 123 and its resting contact and the resting contact of armature 129 and said armature, normally closed contacts controlled by armature 144 and armature 125 and its resting contact to the windings of line relays 115 and 113, respectively. Line relays 113 and relay 115 immediately energize and the former operates release relay 114 from ground by way of armature 130. Release relay 114 upon energizing, grounds the release trunk conductor 102 at armature 133, thus establishing a holding circuit for the line switch C, the said ground extending back to release trunk conductor 102 by way of armature 153 and its resting contact. It is understood, of course, that this ground is placed upon release trunk conductor 102 before the slow acting line relay 201 has time to deenergize. By means of a ground potential upon test contact 213 and its multiples in the banks of the line switches this holding circuit serves to render the connector H' busy to the other line switches; and the busy potential also extends by way of private normal conductor 85 to multiple test contacts in the banks of the connectors thereby guarding the line against intrusion in the usual manner. The connector H' is now ready for the usual impulses.

The calling subscriber may now operate his calling device S' in accordance with the first digit 9 of the desired number and when he does so the line relay 113 is deenergized nine times momentarily. At the first interruption of the circuit produced by the calling device S' the line relay 115 also falls back, in case the negative conductor of the calling line is not grounded too heavily.

The operation of the line relays 113 and 115 of connector H' is substantially like the operation of line relays 28 and 29 of connector H and consequently the detailed description given for the operation of relays 28 and 29 will enable an understanding of the operation of relays 113 and 115. Each time the line relay 113 is deenergized, assuming that relay 115 falls back on the first interruption of the circuit, the vertical magnet 149 is operated by way of the following circuit: from ground through armature 130 of relay 113 and its resting contact, armature 131 and its working contact, off normal springs 137 and 135, resting contact of armature 140 and said armature, slow acting series relay 117, and vertical magnet 149 to battery. By the operation of the vertical magnet the switch shaft and wipers are raised step by step until the latter stand opposite the ninth level of bank contacts. The slow acting relay 117 is energized in series with the vertical magnet and retains its armatures attracted throughout the vertical movement. At armature 145 and its working contact, relay 117 retains the circuit of the vertical magnet intact after the vertical off normal springs have shifted as they do upon the first vertical step. A further result of the energization of relay 117 is that it operates armature 144 to include the resistance R^2 in the impulsing circuit of the line relay 113. At the end of the vertical movement the slow acting relay 117 deenergizes and at armature 144 it replaces relay 115 in the circuit and removes resistance R^2 therefrom, while at armature 145 it shifts the operating circuit from the vertical magnet to the rotary magnet 150.

The calling subscriber may now operate his calling device in accordance with the final digit 0 of the called number and when he does so the rotary magnet 150 receives ten impulses over the following circuit: from ground by way of armature 130 and its resting contact, armature 131 and its working contact, off normal springs 137 and 136, armature 145 and its resting contact, slow acting series relay 118, resting contact of armature 143 and said armature, resting contact of armature 159 and said armature, resting contact of armature 155 and said armature, and rotary magnet 150 to battery. By the operation of the rotary magnet the wipers 161-164, inclusive, are stepped around step by step until they come to rest on the tenth set of contacts in the ninth level opposite which they are raised, being in this case the contacts 165-168, inclusive. Slow acting relay 118 is energized in series with the rotary magnet and retains its armatures attracted throughout the rotary movement and at armature 147 and its upper working contact completes a circuit for the slow acting relay 119. Relay 119 upon energizing, places re-

sistance R^3 in multiple with relay 115 so as to provide a better impulsing circuit, and at armature 151 prepares a circuit for the switching relay 121. A further result of the energization of relay 119 is that it includes resistance R^4 in the circuit of the release trunk conductor 102, only, however, after the slow acting relay 118 has fallen back. At the end of the rotary movement the slow acting relay 118 deenergizes and at armature 147 opens the circuit of slow acting relay 119 and removes a shunt from around resistance R^4 . The switching relay 203 of line switch C is connected in series with resistance R^4 with the result that the potential on release trunk conductor 102 and consequently on private normal conductor 85 is varied, that is, instead of being at approximately the potential of ground as it was before it is changed so as to stand at a point 85 between battery and ground. This operation enables a subscriber to call another subscriber whose substation is located on the same line as the substation of the calling subscriber. This operation, however, has nothing to do with the present call and will be explained fully hereinafter. A further result of the deenergization of slow acting relay 118 is that it closes the test circuit at the normally closed contacts controlled by armature 147.

The operation now depends upon whether the called line is busy or idle. If the called line is busy there is a ground potential upon the test contact 167 with which the test wiper 163 is in engagement and the switching relay 121 being short circuited does not energize. A moment later, however, the slow acting relay 119 deenergizes and at armature 151 completes the following circuit: from grounded test contact 167, by way of test wiper 163, armature 158 and its resting contact, armature 151 and its resting contact, armature 141 and its resting contact, and the upper winding of relay 116 to battery. Relay 116 energizes over the above traced circuit and just before armature 141 breaks away from its resting contact armature 143 makes contact with its working contact thereby closing the following locking circuit for relay 116: from ground by way of armature 132 of release relay 114 and its working contact, lower winding of relay 116, resistance R^5 , working contact of armature 143 and said armature, resting contact of armature 159 and said armature, resting contact of armature 155 and said armature, and rotary magnet 150 to battery. The operation of armature 143 in addition to closing the locking circuit just described for relay 116 also disconnects the rotary magnet 150 from the operating circuit so that in case the calling subscriber should again turn his calling device he will not be able to cause the connector H' to rotate the wipers any further. A further 130

result of the energization of relay 116 is that it connects at armature 142 a lead from the busy signalling machine B' to the upper heavy talking conductor. This operation 5 gives the calling subscriber an audible busy signal to inform him that the called line is, for the time being, inaccessible.

In the present case, however, we may assume that the line of substation A' is idle 10 when called. That being the case, when the slow acting relay 118 deenergizes at the end of the rotary movement, as has been previously described hereinbefore, a circuit is closed at the normally closed contacts controlled by armature 147 for the upper winding of switching relay 121 as follows: from ground, by way of armature 133 and its working contact, normally closed contacts controlled by armature 147, upper winding 15 of switching relay 121, working contact of armature 151 and said armature, resting contact of armature 158 and said armature, test wiper 163, test contact 167, private normal conductor 170, switching relay 215 of line switch C', and stepping magnet 216 to battery. Switching relays 121 and 215 energize in series over the above traced circuit and the latter clears the called line of its normal battery and ground connections in 20 the same manner as the switching relay 203 cleared the line of substation A' in the previous call. In the connector H' the switching relay 121 upon operating opens the operating circuit and establishes a locking circuit for itself at armature 159. This locking circuit extends by way of the working contact of armature 159 and said armature, resting contact of armature 155 and said armature, to battery through rotary magnet 150. As a further result of the energization of switching relay 121, it grounds the test wiper 163 at armature 158 in order to protect the called line against intrusion, and at armatures 156 and 160 completes the connection to the line wipers 161 and 164. An instant later the slow acting relay 119 deenergizes and at armature 153 replaces direct ground on release trunk conductor 102, and at armature 152 removes resistance R 30 from the impulsing circuit.

The connection has now been extended to the desired line and in order to signal, the subscriber at substation A' operates his push button. When he does so ground is placed directly on conductor 84 and resistance R' is included in the bridge across conductors 84 and 85. This operation is substantially the same as was described when the operator in the previous connection operated her ringing key in order to signal the subscriber at substation A' and consequently need not be explained here in detail. It will be sufficient to say that each time the push button P is operated that the line relay 45 113 of connector H' deenergizes and closes

the following circuit for ringing relay 112: from ground by way of armature 130 and its resting contact, armature 131 and its working contact, off normal springs 137 and 136, armature 145 and its resting contact, relay 118, ringing relay 112, working contact of armature 138 and said armature, resting contact of armature 155 and said armature, and rotary magnet 150 to battery. The ringing relay 112 is energized over the above 50 traced circuit but relay 118, however, on account of its comparatively small number of turns is not energized at this time. Relay 112 upon energizing, operates armatures 126 and 128 and thereby projects ringing current out onto the called line. This of course rings the bell at substation A'. Since there is only one subscriber on the line of substation A' it will not be necessary for the calling subscriber to operate his push button in accordance with any code. He will need only to repeat the operation at intervals until the called subscriber responds by removing his receiver. Obviously when the push button P is released the line relay 113 55 energizes again and opens the ringing circuit and generator is removed from the called line.

When the subscriber at substation A' responds by removing his receiver, a circuit is 60 closed for back bridge relay 116 by way of armatures 126 and 128 and their resting contacts and the normally closed contacts controlled by armatures 123 and 125. The calling and called subscribers may now 65 converse with each other, the called subscriber's transmitter being supplied with talking current by way of the upper and lower windings of back bridge relay 116.

When the conversation is finished, the 70 two subscribers will replace their receivers. When the receiver is replaced at substation A' the circuit of the line relays 113 and 115 is broken. Line relays 113 and 115 upon deenergizing, open the circuit of release relay 114. Release relay 114 upon deenergizing, closes at armature 133 the following circuit for release magnet 148: from ground by way of armature 133 and its resting contact, armature 124 and its resting contact, resting contact of off normal spring 134 and said spring, and release magnet 148 to battery. By the operation of the release magnet the switch shaft and wipers are restored to normal position, the circuit of the release magnet being broken at off normal spring 134 by the shaft, when the latter reaches normal position. It will now be assumed that the subscriber at substation A' desires to obtain 80 connection with the subscriber at substation A. When the receiver is removed at substation A' the line switch C' operates in the usual manner to extend the calling line to an idle connector switch. We shall assume in the present case that the connector 85 130

- switch H' is the first one found to be idle and consequently the one selected. That being the case the line and release relays 113 and 114 of the connector H' as well as relay 5 115 energizes in the usual manner. We shall assume further that the connection to the manual exchange in which the line of substation A terminates is obtained by calling 70 71. It will be remembered that there are 10 a plurality of trunk lines leading to the manual exchange. In order to be able to seize the first idle one of these trunk lines the connectors have incorporated in their 15 circuits a rotary feature similar to that of the ordinary selector switch. In order to cause the connector switch to rotate over to the next set of contacts when one is found to be busy and not merely remain upon the contacts and send back a busy signal the two 20 private contacts are connected together as shown in Figure 5. In the last trunk line of the group, however, the two private contacts are not jumpered together but are left open as in the case of an individual line. 25 The result is that if a connector switch tries all of the trunks and finds them all busy, when it comes to the last one it tests it and upon finding it busy does not rotate any further but sends back a busy signal to the 30 calling subscriber. Assuming that there are three trunk lines between the manual and the automatic exchanges, the first two sets of private contacts are connected as indicated in the left hand portion of Fig. 5. 35 The connection having been extended to the connector H' the calling subscriber may now operate his calling device in accordance with the first digit 7 of the desired number and when he does so the connector H' steps 40 its wipers up until they stand opposite the seventh level of bank contacts. The calling subscriber now operates his calling device in accordance with the digit 1. This time the connector H' rotates its 45 wipers one step at the same time operating the slow acting relays 118 and 119 in the manner hereinbefore described. At the end of the rotary movement the slow acting relay 118 deenergizes and completes at armature 146 the test circuit that is used only 50 when the switch is operating as a selector to pick out an idle trunk line, and at the normally closed contacts controlled by armature 147 completes the regular test circuit that 55 determines whether or not the trunk upon which the wipers are standing is busy. The operation now depends upon whether 60 the first trunk line is busy or idle. Assuming that it is busy there is a ground potential present on the test contact 176, the switching relay 121 is short circuited and since test contact 176 is multiplied with test contact 175 the latter contact is grounded also thereby operating the stepping relay 120 over 65 the following circuit: from ground by way of test contact 175, test wiper 162, armature 157 and its resting contact, resting contact of armature 146 and said armature, resting contact of the armature of rotary magnet 150 and said armature, and stepping relay 120 to battery. Upon energizing, relay 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

ner to project generator out over the called line. Since the called line is now extended to the manual exchange by way of trunk conductors 24 and 25 the drop 15 in front 5 of the operator is operated.

The operator, upon noting the operated condition of drop 15, restores it to normal and inserts the answering plug of an idle cord circuit into the jack J'. She then 10 throws her listening key in order to converse with the calling subscriber and ascertain who he desires connection with. The remainder of the operation is old and since it has nothing in particular to do with the 15 invention it need not be described in detail. It will be sufficient to say that the trunk conductors 88 and 90 of the connector H are reversed according to the usual practice, when calls are extended from an automatic 20 to a manual exchange by way of a two way trunk. That being the case, the relay 17 is operated as soon as the connection is extended to it over the conductors 24 and 25. This is done in order that the operator may get 25 answering supervision as soon as she inserts the plug of the cord circuit into the jack J' and of course as soon as the subscriber who has made the call hangs up thereby removing battery from the trunk conductors 24 30 and 25 the supervisory lamp of the cord circuit which is inserted into the jack J' lights to give the operator a disconnect signal and she will pull down the connection in the usual manner. When the subscriber at sub- 35 station A' replaces his receiver the connector H' releases in the usual manner which need not be here explained.

It will now be explained how a subscriber may call another subscriber whose telephone 40 substation is located on the same line as that of the calling subscriber. For this purpose it will be assumed that the subscriber at substation A' desires to obtain connection with the subscriber at substation A³. It will be 45 assumed further that the code by which the subscriber at substation A³ is signalled consists of three short rings.

When the subscriber at substation A' removes his receiver the line switch C operate in the usual manner to pick out an idle 50 trunk line leading to a connector, and we shall assume in the present case that the line switch C upon operating obtains access to the connector H'. That being the case when 55 the called subscriber operates his calling device in accordance with the first digit 8 of the desired number the connector H' raises its wipers 161-164, inclusive, step by step until they stand opposite the eighth level of bank 60 contacts. When the second digit 9 is called the wipers 161-164, inclusive, are rotated step by step until they come to rest on the ninth set of contacts in the level opposite which they are raised, being in this case the bank 65 contacts 174-177, inclusive.

While the wipers are being rotated the slow acting relays 118 and 119 are energized in the usual manner. At the end of the rotary movement the slow acting relay 118 de-energizes and at armature 147 removes the 70 shunt around resistance R' and completes at the normally closed contacts controlled by said armature, the test circuit for the upper winding of relay 121. Obviously since the subscriber at substation A' is calling another 75 subscriber whose substation is on the same line the test wiper 163 comes into engagement with the private normal conductor 85 of the calling line switch. Ordinarily this would result in the usual busy signal being 80 sent back but with a connector such as the connector H' the including of the resistance R⁴ in the circuit of release trunk conductor 102 results in the potential on the private 85 normal conductor 85 being altered sufficiently to allow the switching relay 121 to energize. Switching relay 121 upon energizing, completes the connection through to the called line which in this case is the same line as the one that is calling. It follows, therefore, that the back bridge relay 116 energizes at once. 90

The subscriber at substation A' will now operate the push button P three times in accordance with the code of substation A³ and 95 each time he does so ringing current is projected out on the line and the subscriber at substation A³ is signalled.

When the subscriber at substation A³ hears 100 his bell ringing he responds by removing his receiver. The two subscribers may now converse with each other in an obvious manner. When the conversation is finished both subscribers will hang up their receivers and release takes place in the usual manner. 105

If the subscriber at A² were the called subscriber instead of the subscriber at A³ the only difference in the operation is that the push button is operated differently in order to produce a different code signal. 110

In the lower part of Fig. 4 there is shown the repeater D. This is a two way repeater and it is used for connections to and from another exchange that may be substantially like the No. 2 exchange which has just been 115 described. The trunk line with which the repeater D is connected is the trunk line comprising conductors 260 and 261. It will be remembered that on the other end of the trunk line 260 and 261 there is another repeater similar to repeater D and that access to the repeater D and consequently to the trunk line to which it is connected is obtained by calling O¹. There may be, and usually 120 are, a plurality of such trunk lines. Accordingly the two private conductors associated with each of the sets of contacts into which the trunk lines leading to repeaters such as repeater D terminate are tied together in order that the connectors may automatically 125 130

rotate to pick out an idle trunk line. In the case of a connector calling the repeater D and also the other repeaters similar to it, the connector will switch the calling line through 5 in the same manner as a selector, when an idle trunk is found. This is made possible by the springs 36 and 122 of connectors H and H', respectively. These springs are mounted on the respective switches in such 10 a manner that they are operated only when the switch wipers are stepped up to the tenth level of bank contacts.

Keeping the above facts in mind we shall assume now that the subscriber at substation A desires to obtain connection with a subscriber whose line terminates in the No. 3 exchange, reached by way of trunk line 260-261. When the subscriber at substation A removes his receiver the operator is 20 signalled in the usual manner and after she answers and obtains the desired information she inserts the other plug of the cord circuit in use into the jack of an idle trunk line extending to the nearer C. A. X., the 25 jack J' for example and throws the key K' thereby inserting her calling device S into the circuit all in the manner previously explained.

The operator will now operate her calling 30 device in accordance with the first digit 0 of the desired number and as a result the connector H raises the wipers 76-79, inclusive, step by step until they stand opposite the tenth level of bank contacts.

35 When the calling device is again turned it will be in accordance with the second digit 1 of the desired number. In response to the calling of the second digit the connector H steps the wipers into engagement with the 40 first set of contacts in the level opposite which they were raised. After the end of the rotary movement, slow acting relay 32 deenergizes. Relay 32, upon deenergizing, shifts the circuit of relay 34 so as to include 45 relay 33.

The operation now depends upon whether the first trunk is busy or idle. If the first trunk is busy there is a ground potential 50 on test contacts with which the test wipers 77 and 78 are in engagement, it being remembered that in this case the two test contacts are connected together. That being the case, relay 34 does not deenergize when its circuit is shifted as explained but is 55 maintained energized over a circuit that includes relay 33, which is the stepping relay while the automatic rotary movement is taking place. Stepping relay 33 is energized now in series with relay 34 and at 60 armature 62 shifts the circuit so that the two relays 33 and 34 are held up from ground on release trunk conductor 89 instead of from ground by way of the busy test contact. This operation is the same as 65 that described in connection with the call

in which the subscriber at substation A called a subscriber at substation A'. A further result of the energization of stepping relay 33 is that it closes the following circuit for rotary magnet 69: from ground by 70 way of the busy test contact with which test wiper 77 is in engagement, test wiper 77, armature 61 and its working contact, resting contact of armature 72 and said armature, and rotary magnet 69 to battery. Rotary magnet 69 upon energizing, steps the wipers into engagement with the next set of contacts and at armature 66 closes a new circuit for relay 34, at the same time opening the circuit of the stepping relay. Stepping 80 relay 33 upon deenergizing, opens the circuit of rotary magnet 69, which thereupon deenergizes and closes again the circuit of the stepping relay. If the second set of contacts is busy the same cycle of operation 85 is repeated, and the operation continues in this manner until an idle set of contacts is reached.

In the present case, however, we shall assume that the tenth or last trunk line or 90 the trunk line terminating in contacts 88'-91, inclusive is the first one found idle. This being the case, armature 66 of rotary magnet 69 upon falling back closes a circuit for stepping relay 33 as usual in series with 95 relay 34 but because the test contact 90' with which test wiper 78 is in engagement is not grounded, stepping relay 33 fails to energize and relay 34 deenergizes. Relay 34 upon deenergizing, completes the following 100 circuit: from ground by way of the lower winding of switching relay 35, resting contact of armature 65 and said armature, resting contact of armature 73 and said armature, test wiper 78, test contact 90', release 105 trunk conductor 253, armature 239 (Fig. 4) and its resting contact, release trunk conductor 256, switching relay 217, and stepping magnet 218 to battery. Switching relays 35 and 217 energize in series over this circuit 110 but the energization of the latter has no function at this time. Switching relay 35 upon energizing, grounds the test wiper 78 at armature 73, and at armatures 70 and 74 completes the connection to the line wipers 115 76 and 79, and at armature 72 closes the usual locking circuit for itself. When this locking circuit is closed the following circuit also is closed for switching relay 26: from ground by way of the working contact of armature 73 and said armature, test wiper 78, test contact 90', resistance R^o, test contact 89', test wiper 77, armature 61 and its 120 resting contact, working contact of tenth level spring 36 and said spring, upper winding of switching relay 26, working contact of armature 72 and said armature, and rotary magnet 69 to battery. Upon energizing, switching relay 26 extends the connection by way of armatures 37 and 39 and 125 130

their working contacts, resting contacts of armatures 64 and 68 and said armatures, armatures 70 and 74 and their working contacts, line wipers 76 and 79, contacts 88' and 91, conductors 252 and 254, normally closed contacts controlled by armatures 250 and 251, to line relays 232 and 231 of the repeater D. The said relays immediately energize and close at armatures 247 and 248 10 multiple points in the circuit of release relay 230. Release relay 230, upon energizing, closes at armature 244 a circuit for relay 228. Relay 228, upon energizing, disconnects the release trunk conductor 253 15 from release trunk conductor 256 of the incoming line switch C² and connects it to ground. This ground potential extends by way of release trunk conductor 253, test contact 90', test wiper 78, and armature 73 and 20 its working contact to switching relay 35 of connector H to hold the said relay energized. A branch of this circuit also extends by way of resistance R⁹ and test contact 89' 25 to hold switching relay 26 energized. It is understood of course that this circuit is closed before the slow acting release relay 30 in the connector H has time to deenergize. Returning now to repeater D, when ground 30 is placed on release trunk conductor 253 a circuit is closed for the lower or polarizing winding of electropolarized relay 235. This winding consists of few turns of high resistance and is not able to operate the relay. 35 As a further result of the energization of relay 228 it not only shifts the connection of the release trunk conductor 253 as before explained, but also disconnects trunk conductors 260 and 261, at armatures 238 and 240, from the conductors 255 and 257, 40 respectively, and connects them to a closed bridge in the repeater D extending as follows: from armature 240 and its working contact, by way of impedance 227, upper winding of electropolarized relay 235, working contact of armature 246 and said armature, to the working contact of armature 238 and said armature. It will be remembered 45 that on the other end of the trunk line 260 and 261 there is a repeater similar to repeater D and associated therewith is a line switch similar to line switch C². That being the case, when the bridge is closed across trunk line 260 and 261 at repeater D the line switch on the other end of the trunk, similar 50 to line switch C², is operated in the usual manner to pick out an idle trunk line leading to a local connector. The electropolarized relay 235 is not operated at this time because the current flowing in its upper 55 winding opposes that flowing in its lower winding.

The operator may now operate her calling device in accordance with the remaining digits of the desired number and when she does so the connector in the distant exchange 60 steps its wipers into engagement with the desired set of contacts, the impulses being repeated at armature 246 and its working contact. Upon the sending of the first impulse, line relay 232 also falls back and at 70 armature 248 closes a circuit for slow acting relay 229 by way of armature 245 and its working contact. Upon energizing, relay 229 shunts relay 232 with resistance R⁵ at 75 armature 241, opens at armature 243 a point in the circuit used for relaying ringing impulses so as to prevent possible interference, and at armature 242 closes the bridge across trunk conductors 260 and 261 by a more direct path so as to improve the impulses sent 80 to the distant connector. At the end of the series of impulses slow acting relay 229 falls back and prepares the circuit for relaying ringing impulses at armature 243. When the next series of impulses is sent relay 229 85 operates as before and falls back again upon their cessation.

The operator may now operate her ringing key in the usual manner and when she does so relay line 231 of repeater D deenergizes 90 and line relay 232 remains energized. With this condition existing trunk conductor 260 is connected to ground by way of the following circuit: from armature 238 and its working contact, by way of armature 246 and its resting contact, working contact of armature 249 and said armature, and the resting contact of armature 243 and said armature to ground. This of course has the same 95 effect on conductor 260 and consequently the relay in the connector switch on the other end of said conductor as though a ringing key were actually pressed at repeater D to ground the conductor 260. Conductor 261 at this time is grounded over the bridge previously traced through repeater D except that the resistance R⁶ is now included in this bridge since the armature 246 is at this time in a deenergized position. The utility 100 of resistance R⁶ is the same as was described for the resistance R¹⁰ at the operator's position. It will now be seen that the repeater D relays the circuit conditions into the connector switch on the other end of trunk line 105 260 and 261 to cause the connector to send out a ringing current. The operator will repeat the ringing operation as many times as may be necessary in order to attract the attention of the called subscriber. When 110 the called subscriber answers he causes battery to be reversed in the trunk conductors 260 and 261 in a manner that will be explained fully hereinafter. When the current flow is reversed in trunk conductors 260 and 261 it is also reversed in the upper winding 115 of the electropolarized relay 235 included in a bridge thereof. The two windings of relay 235 which heretofore have opposed each other now assist each other in operating the said relay. Upon energizing, relay 235 120 125 130

reverses the conductors 252 and 254 at armatures 250 and 251 as regards their connection with line relays 231 and 232. The final result is that polarized relay 17, Fig. 5, is operated to give the operator answering supervision in the usual manner. The two subscribers may now converse with each other in the usual manner. When the conversation is finished both subscribers replace 10 their receivers, the replacing of the receiver at substation A bringing in the usual disconnect signal. When the receiver is replaced at the called substation in the distant exchange the current flow in conductors 260 and 261 is reversed back to normal with the result that relay 239 retracts its armature thereby reversing the current flow in conductors 252 and 254 to normal. This re-lights the lamp L² in the usual manner and 20 the operator pulls down the connection.

Attention may now be called to the fact that the local connectors in the two C. A. X.'s are not arranged to reverse battery when a call is answered. Due to the numerous 25 other duties, including the completing of reverting calls, that the connector must perform it has not yet been found desirable to arrange a connector of this type to reverse battery. In order to take care of the reverting of battery on interexchange calls a novel arrangement is made use of. Since the equipment in the two ends of the trunk line 260—261 is identical a description of the operation of one will serve for the other. Accordingly it will now be assumed that a call 30 is coming from the No. 3 exchange by way of trunk line 260—261. When the line switch C² extends the connection to a connector, the connector H' for example, the switching relay 217, in addition to closing the usual circuits, closes also at armature 280 a circuit to wiper 281. Now when the called subscriber answers, the back bridge relay 116 energizes and at armature 172 closes the following circuit: from ground by way of armature 175 of switching relay 121 and its working contact, working contact of armature 172 and said armature, conductor 104, contact 262, wiper 281, working contact of armature 280 and said armature, conductor 258, and reversing relay 226 to battery. Reversing relay 226 energizes and at armatures 236 and 237 reverses the trunk conductors 260 and 261 as regards their connection with 45 the line relays at connector H'. This obviously results in the reversal of the direction of current flow in the said conductors.

We shall now assume that the subscriber at substation A⁴ desires to obtain connection 50 with some subscriber located in the exchange on the other end of trunk conductors 260 and 261. When the subscriber at substation A⁴ removes his receiver to initiate the call line switch C' is operated to pick out an idle connector switch. We shall assume in

the present case that the connector switch H' is the first one found idle and consequently the one seized. That being the case, the relays 112 and 113 energize in series over the subscriber's loop, and release relay 114 70 is energized and grounds the release trunk conductor 102, thereby establishing the usual holding circuit, and the connector is made ready for operation in the usual manner.

The subscriber may now operate his call- 75 ing device in accordance with the first digit 0 in the desired number and when he does so the connector H' steps its wipers up step by step until they stand opposite the tenth level of bank contacts.

The calling subscriber may now operate his calling device in accordance with the second digit 1 of the desired number and thereupon the wipers are rotated one step.

The operation now depends upon whether 85 the first trunk is busy or idle. Assuming that the trunk is busy the slow acting relay 118, upon deenergizing, closes at armature 146 the following circuit for stepping relay 120: from ground by way of the connecting jumper to the test contact with which test wiper 162 is in engagement, test wiper 162, armature 157 and its resting contact, resting contact of armature 146 and said armature, resting contact of the armature of the rotary magnet 150 and said armature, and stepping relay 120 to battery. Stepping relay 120 upon energizing, closes a circuit at armature 154 for slow acting relay 119 before the said relay has time to deenergize, and at armature 155 closes the following circuit for the rotary magnet 150: from ground by way of armature 139 and its working contact, normally closed contacts controlled by armature 147, working contact of armature 155 and said armature, and rotary magnet 150 to battery. Upon energizing, rotary magnet 150 steps the wipers over the next set of contacts and at the same time operates its armature to break the circuit of stepping relay 120. 110 Stepping relay 120 upon deenergizing opens the circuit of the slow acting relay 119 and also opens the circuit of the rotary magnet 150 which, thereupon, deenergizes and closes again the circuit of the stepping relay 120. 115

The operation now depends upon whether the second set of contacts is busy or idle. If it is busy the same cycle of operation is repeated over and over until an idle or ungrounded set of contacts is reached. We 120 shall assume in the present case that the trunk line terminating in contacts 181—184, is the first one found idle and consequently the one selected. That being the case the arrival of test wiper 163 upon test contact 125 183, closes the following circuit for switching relay 121: from ground by way of the upper winding of switching relay 121, working contact of armature 151 and said armature, resting contact of armature 158 and 130

said armature, test wiper 163, test contact 183, release trunk conductor 253, armature 239 of relay 228 of the repeater D and its resting contact, release trunk conductor 256, 5 switching relay 217 of line switch C², and stepping magnet 218 to battery. Switching relays 121 and 217 energize in series over the above traced circuit. Switching relay 217 upon energizing, clears the called line of its 10 normal battery and ground connections. In connector H' switching relay 121 upon energizing, completes a locking circuit for itself at armature 159 in the usual manner and at armature 158 grounds the release trunk conductor 253 in order to make it busy immediately. This ground also extends by way 15 of resistance R¹¹, test contact 182, test wiper 162, armature 157 and its working contact, tenth level spring 122 and its working contact, 20 switching relay 111, working contact of armature 159 and said armature, resting contact of armature 155 and said armature, and rotary magnet 150 to battery. Upon energizing, switching relay 111 extends the 25 calling line by way of armature 123 and their working contacts, resting contacts of armature 126 and 128 and said armatures, armatures 156 and 160 and their working contacts, line wipers 161 and 164, contacts 30 181 and 184, conductors 252 and 254, normally closed contacts controlled by armatures 250 and 251 to line relays 232 and 231 of repeater D. Line relays 232 and 231 in repeater D immediately energize over the 35 calling subscriber's loop and prepare the switch for operation in the usual manner. From this point the call continues in the same manner as previously described in which the subscriber at substation A called 40 a subscriber whose line terminates in the distant exchange and, consequently, it need not be described in detail.

In the two calls described, that were for a subscriber whose line terminates in the 45 No. 3 exchange, no mention is made about what happens when all ten trunk lines such as the trunk line 260—261 are busy. Such explanation will now be given.

In the case of the connector H when its 50 wipers arrive on the tenth set of contacts in the tenth level or the contacts 88—91, inclusive, and find them busy relay 33 energizes again and closes the usual circuit for the rotary magnet 69 but owing to the 55 high resistance of R⁹ the rotary magnet cannot energize and consequently the usual busy signal is sent back to the calling operator.

When the wipers of connector H' arrive 60 on the tenth set of contacts in the tenth level and find them busy the usual circuit is closed for the stepping relay 120 but owing to the high resistance of R¹¹ the said relay cannot energize. A moment later 65 slow acting relay 119 falls back and closes

the usual busy test circuit with the final result that an audible busy signal is sent back to the calling subscriber to inform him that he cannot, for the time being, obtain the desired connection.

Having fully described and ascertained the features of my invention what is considered to be new and desired to have protected by Letters Patent will be pointed out in the appended claims.

What I claim as my invention is:

1. In a telephone system, a calling line, an automatic switch controlled over the said calling line to connect with a called line, the switch being normally operable regardless 80 of an abnormal condition of the line, and means whereby the switch is prevented from operating in case the abnormal condition is such as to interfere with the subsequent release of said switch.

2. In a telephone system, a telephone line in abnormal condition, an automatic switch adapted to be controlled over said line to connect with another line regardless of said abnormal condition, and means effective to 90 prevent the operation of said switch in case the abnormal condition is such as to prevent the subsequent release of the switch.

3. In a telephone system, telephone lines, some in normal and some in abnormal condition, an automatic switch having different operating and releasing characteristics, the switch being operable over any calling line whether such line is in normal condition or not, while the switch can be released only if the calling line is in normal condition, and means for preventing the operation of said switch over a calling line whose condition is so abnormal that if the switch were permitted to operate its subsequent release 95 would be interfered with.

4. In a telephone system, telephone lines, some in normal and some in abnormal condition, an automatic switch having different operating and releasing characteristics, the switch being operable over any calling line whether such line is in normal condition or not, while the switch can be released only if the calling line is in normal condition, means in said switch for testing the condition of a 110 calling line in case it is attempted to operate said switch over such line, and means for preventing the operation of the said switch in case the test indicates that if the switch were permitted to operate its subsequent release 115 would be interfered with.

5. In a telephone system, telephone lines, some in normal and some in abnormal condition, an automatic switch controllable over a calling one of said lines and having main and auxiliary functions to perform in connecting with and signalling a called line, the said switch being adapted to perform its main functions whether the calling line is in 120 normal condition or not, while it can per-

form certain of its auxiliary functions only if the calling line is in normal condition, and means for preventing said switch from performing its main functions under control of a calling line whose condition is so abnormal that the subsequent performance of the auxiliary functions of said switch would be interfered with.

6. In a telephone system, a telephone line 10 having a ground on one conductor thereof, an automatic switch adapted to be controlled over said line to connect with another line, and means effective to prevent the operation of said switch in case the said ground is of 15 such low resistance that it would prevent the subsequent release of said switch, although so far as the said ground is concerned the said switch could be operated.

7. In a telephone system, an automatic 20 switch, a calling line and means for extending it to said switch, a relay in said switch connected from one conductor of said line to the non-grounded pole of the exchange battery, a second relay in said switch connected 25 from the other conductor of said line to ground, means for interrupting the line circuit at the subscriber's station to cause deenergizations of said second relay, means for operating said switch controlled by said second relay, a non-inductive resistance, and a 30 relay energized during the operation of said switch to substitute said resistance for the said first relay.

8. In a telephone system, an automatic 35 switch, a calling line and means for extending it to said switch, a relay in said switch connected from one conductor of said line to the non-grounded pole of the exchange battery, a second relay in said switch connected 40 from the other conductor of said line to ground, means for interrupting the line circuit at the subscriber's station to cause deenergizations of said second relay, means controlled by said second relay in response 45 to said interruptions for operating said switch to connect with a called line, a device at the subscriber's station for opening a normally closed connection between the line conductors and for connecting one conductor to 50 ground, the said second relay being deenergized while the first relay is held up, and means controlled by said relays jointly for signalling the called subscriber.

9. In a telephone system, an automatic 55 switch, a calling line and means for extending it to said switch, a relay in said switch connected from one conductor of said line to the non-grounded pole of the exchange battery, a second relay in said switch connected 60 from the other conductor of said line to ground, means for interrupting the line circuit at the subscriber's station to cause deenergizations of said second relay, means controlled by said second relay for operating said switch to connect with a called line, a 65

device at the subscriber's station for opening a normally closed connection between the line conductors and for connecting one conductor to ground, the said second relay being deenergized while the first relay is held up, means controlled by said relays jointly for signalling the called subscriber, a relay energized when the called subscriber answers to reverse the two conductors of the calling line with respect to their connections to said first and second relays, means for releasing said switch effective when both said relays are deenergized, and a resistance connected in shunt of said normally closed connection to maintain said first relay energized in case 70 the said device is actuated after the called subscriber has answered, thereby preventing said switch from releasing.

10. In a telephone system, a two way trunk line terminating in an automatic switch and accessible at the same end to other automatic switches, a relay mechanism in said first switch controllable over said trunk line from the other end thereof to cause the operation of said switch, a switching relay and a circuit for energizing it after said switch has operated to disconnect the trunk from said relay mechanism and to connect it instead to the wipers of said switch, and another circuit for energizing said switching relay effective in case said trunk line is taken for use by one of said other switches.

11. In a telephone system, a calling line, a group of trunk lines, an automatic side- 100 switchless connector switch controllable over the calling line to select said group of trunk lines among other lines accessible to said switch, a motor magnet and means for operating the same automatically to cause said switch to select the first idle trunk in said group, said means including a stepping relay for sending impulses to said magnet, means for holding said relay energized in case all of said trunks are busy, and contacts controlled by said relay for connecting the calling line with a source of busy signalling current.

12. In a telephone system, two kinds of lines, an automatic switch adapted for use 115 by a calling line of either kind for extending connection to a called line, and means controlled by the response of the called subscriber for reversing the direction of current flow in the calling line only in case such 120 calling line is of a particular kind.

13. In a telephone system, a connector switch, local lines and incoming trunk lines having access to said switch, there being means for operating said switch over either a local line or a trunk line to connect with a called line, and means in said switch for reversing the direction of current flow in the direction of the calling subscriber in case the call comes over a trunk line, while if a 125 130

local line is calling the current flow therein is not reversed.

14. In a telephone system, a local line and an incoming trunk line each terminating in an individual switch, a local trunk line accessible to both switches and extending to a connector switch, an extra conductor in said local trunk line accessible only to the individual switch which is associated with said 5 incoming trunk line, means for operating either individual switch to connect with said local trunk line and for operating said connector to connect with a called line, and relay mechanism operated when the called subscriber answers in case he has been called by way of said incoming trunk line for reversing the direction of current flow in such 15 trunk line, said mechanism being controlled over said extra conductor.
- 20 15. In a telephone system, a two-way trunk line terminating in an automatic switch and accessible at the same end to other switches, a line relay in the first switch controllable over said trunk line to cause the operations of said first switch, a 25 cut-off relay and a circuit for energizing it after the switch has operated to disconnect said line relay from said trunk, and another circuit including a second winding 30 on said cut-off relay for energizing it to cut-off said line relay when said trunk line is seized by one of said other switches.

- 35 16. In a telephone system, a connector switch having a test relay adapted to pull up and connect up the line wipers responsive to a non-busy potential on the test contact of a called line, a second test relay adapted to pull up and place a busy tone on the calling line responsive to a busy potential on the 40 test contact of a called line, circuit arrangements such that said first test relay is connected to the selected test contact after said switch has been operated, and circuit arrangements such that said second relay is 45 then connected to the selected test contact in case said first test relay does not operate.

- 50 17. In a telephone system, a connector switch having wipers, a test relay, means for moving said wipers into engagement with the contacts of a desired line, a slow-acting relay held energized during the said movement of said wipers, another relay, means for operating said other relay at the end 55 of the movement of said wipers to open the circuit of said slow-acting relay and to connect up said test relay in a circuit including the test contact of the called line, means controlled by said test relay and in response to its finding an idle potential on the test 60 contact of a line for completing the connection to said line, and means controlled by said slow-acting relay when it falls back for opening the test circuit extending through said test relay.

- 65 18. In a telephone system, a connector

switch having wipers, two test relays, means for operating said switch to bring said wipers into engagement with the contacts of a desired line, a slow-acting relay energized during the time in which said wipers are 70 being brought into engagement with the desired contacts, means operative upon the cessation of the operation of said switch for opening the circuit of said slow-acting relay and for connecting up the first of said test 75 relays in a circuit extending from one pole of the exchange battery to the selected test contact, and means controlled by said slow-acting relay when it falls back for opening the said circuit for the said first test relay 80 and for connecting up the second of said test relays in a circuit extending from the other pole of the exchange battery to said test contact.

19. In a telephone system, a two-way trunk, an automatic impulse relaying repeater associated with said trunk at one end thereof, means including automatic switches for setting up connections over said trunk in either direction, and means in said repeater responsive to the answering of the called subscriber for reversing the current flow in either end of said trunk when that end is the calling end.

20. In a telephone system, an automatic switch, a calling line, means including another automatic switch for extending a connection from said line to the first of said switches, a release trunk conductor for said first switch, means for holding said other switch in its operated position responsive to a holding potential on said conductor, a relay in said first switch connected between one pole of the exchange battery and one line conductor, another relay in said first switch connected from the other pole of the exchange battery to the other line conductor, a circuit for energizing said relays in series over the calling line when said connection is extended to said first switch, a release relay, contacts controlled thereby for placing a holding potential on said release trunk conductor, contacts controlled by one of said line relays for closing an energizing circuit for said release relay, and contacts on the other line relay for placing a holding potential on said release trunk conductor direct.

21. In a telephone system, an automatic switch, subscribers' lines divided into groups accessible thereto, means for operating said switch vertically in order to select one of said groups and for then rotating said switch into connection with one of said lines, a test wiper for said switch, a test relay in 120 said switch, a slow-acting relay energized during the rotary movement of said switch, a third relay for connecting said test wiper to said test relay, and a circuit for said 125 third relay closed by said slow-acting relay.

22. In a telephone system, an automatic switch, called lines accessible thereto divided into groups and subgroups, said switch having a directly controlled movement to select groups and subgroups and an automatic movement to select an idle line in the selected subgroup, a relay energized only during the movement of said switch in selecting subgroups, a test wiper for said switch, a test relay for said switch, a third relay for connecting said test wiper to said test relay, a circuit for energizing said third relay completed upon the operation of said first relay, and means for maintaining said third relay energized during the automatic movement of said switch.

23. In a telephone system, an automatic switch, called lines accessible thereto divided into groups, said switch having a directly controlled movement to select a group of lines and an automatic hunting movement to select an idle line in the selected group, a relay energized during the movement of said switch in selecting a group of lines, a slow-acting relay energized in response to the energization of the first relay, a test wiper, a test relay, means for deenergizing said first relay at the end of said directly controlled movement, means controlled by said first relay when it deenergizes for connecting said test relay to said test wiper, for initiating the automatic hunting movement of the switch, and for opening the circuit of said slow-acting relay, means for maintaining said slow-acting relay energized during the automatic hunting movement of the switch, and means controlled by said slow-acting relay when it falls back for disconnecting said test relay from said test wiper.

40 24. In a telephone system, an automatic switch, called lines accessible thereto divided into groups, said switch having a directly controlled movement to select a group of lines and an automatic hunting movement to select an idle line in the selected group, a relay energized during the movement of said switch in selecting a group of lines, a slow-acting relay energized in response to the energization of the first relay, a test wiper, two test relays, means for deenergizing said first relay at the end of said directly controlled movement, means controlled by said first relay when it deenergizes for connecting the first of said test relays to said test wiper, for initiating the automatic hunting movement of the switch, and for opening the circuit of said slow-acting relay, means for maintaining said slow-acting relay energized during the automatic hunting movement of the switch, and means controlled by said slow-acting relay when it falls back for disconnecting the first test relay from the test wiper and for connecting the second test relay thereto.

65 25. In a telephone system, a trunk line

connecting an automatic exchange with a manual exchange, means including automatic switches in the automatic exchange for completing connections over said trunk line originating at either exchange, a polarized relay at the manual exchange individual to said trunk line, a supervisory signal controlled by said relay, and means operated automatically in both automatic to manual and manual to automatic calls for reversing the direction of current flow in said trunk line to actuate said relay when the automatic subscriber involved hangs up his receiver.

26. In a telephone system, a trunk line connecting an automatic exchange with a manual exchange, means including automatic switches in the automatic exchange for completing connections over said trunk line originating at either exchange, a polarized relay at the manual exchange individual to said trunk line, a supervisory signal controlled by said relay, and means operated automatically in an automatic to manual call to actuate said relay when the automatic subscriber involved replaces his receiver and in a manual to automatic call to deactivate or actuate said relay when the automatic subscriber involved removes or replaces his receiver, respectively.

27. In a telephone system, a trunk line extending between an automatic and a manual exchange, an automatic switch at said automatic exchange, an operator's position at said manual exchange, means including said switch for establishing a talking connection between said exchanges from the automatic exchange over said trunk line, means including said switch for establishing a talking connection between said exchanges from the manual exchange over said trunk line, a polarized relay at said manual exchange individual to said trunk line, and means in said switch in calls from the automatic exchange to the manual exchange for actuating said relay when the automatic subscriber involved replaces his receiver and in calls from the manual exchange to the automatic exchange for actuating said relay when the operator seizes said trunk line, for deactivating said relay when the automatic subscriber involved removes his receiver, and for reactuating said relay when the automatic subscriber involved replaces his receiver.

28. In a telephone system, a calling line, an automatic switch under the control of said calling line and having two line relays, one of said line relays being connected between one conductor of the calling line and ground, and the other line relay being connected between the other conductor of the calling line and the ungrounded pole of the exchange battery, an operating circuit for said switch including normally closed contacts on both said relays, and means respon-

sive to the first impulse of current delivered over said operating circuit responsive to the first interruption at the calling device on the calling line for by-passing said normally closed contacts on said other line relay.

29. In a telephone system, a calling line, an automatic switch controlled over said calling line by means of two line relays to connect with a called line, each step of said automatic switch being controlled by one of said line relays, and means whereby the first step only of said automatic switch is dependent upon the successful operation of the other line relay.

15 30. In a telephone system, calling lines, an

automatic switch for extending any one of said calling lines into connection with called lines, two line relays in said switch controlled separately over said calling line, an operating circuit in said switch, and means whereby the transmission of the first impulse of current over said operating circuit is controlled jointly by both line relays, and whereby the transmission of further impulses over said operating circuit is controlled by one relay only.

In witness whereof, I hereunto subscribe my name this 9th day of March, A. D. 1921.

BERNARD D. WILLIS.
